UNITED STATES PATENT OFFICE

WILLIAM KLINGE, OF WASHINGTON, DISTRICT OF COLUMBIA, ASSIGNOR OF ONE-HALF TO
JAMES McMANUS, OF WASHINGTON, DISTRICT OF COLUMBIA.

OYSTER-SHUCKING APPARATUS.

No. 880,222.

Specification of Letters Patent.

Patented Feb. 25, 1908.

Application filed November 23, 1907. Serial No. 403,474.

To all whom it may concern:

Be it known that I, WILLIAM KLINGE, a citizen of the United States, residing at Washington, in the District of Columbia, have invented new and useful Improvements in Oyster-Shucking Apparatus, of which the following is a specification.

This invention relates to an oyster shucking apparatus, the object of the invention being to provide a simple, efficient, and comparatively inexpensive construction of apparatus of this character which may be conveniently operated, which is adapted to act equally well upon large and small oysters, and whereby the operation of shucking oysters may be rapidly and economically performed.

The invention consists of the features of construction, combination and arrangement of parts hereinafter fully described and claimed, reference being had to the accompanying drawings, in which:—

Figure 1 is a side elevation of an oyster shucking apparatus embodying my invention. Fig. 2 is a top plan view of the same. Fig. 3 is a front view of the apparatus.

Referring to the drawings, the numeral 1 designates a supporting frame, which may be of any preferred form and construction, but which is preferably composed of angle iron and comprises a base 2 from which rise four corner standards or uprights 3 connected at their upper ends by a top or head plate 4, the parts being additionally tied or connected in any desired manner. As shown, the top plate has a slight downward and forward inclination, and cross-braces 5 connect the front and rear standards at each side of the frame.

The oysters are designed to be individually treated and to be clamped during the shucking operation between relatively stationary and movable clamps 6 and 7. The stationary clamp 6 comprises a cross piece extending between the front standards below the forward edge of the top plate 4, which latter is provided in said edge with a recess 8 for the free downward movement of the splitting knife, hereinafter described, while the movable clamp 7 comprises a partially circular body disposed at the front of the machine and reinforced by strengthening flanges 9 and 10. The said movable clamp is arranged for use at the front of the machine

for movement between the front corner standards and is provided at its upper end with a shelf 11 to support the oyster and with a retaining flange or series of retaining fingers 12 projecting over the shelf to retain the oyster in engagement therewith.

In practice, the oyster is laid upon the shelf with its butt or hinged end inward and bearing on the clamp 6 and its thin or mouth end outward and disposed beneath the retaining flange or fingers 12, the oyster being held at an inclination for the proper operation thereon of the splitting and severing knives, as hereinafter described.

The movable clamp normally inclines outwardly at its upper end, by which a space of sufficient size is provided for the reception of the largest oyster between the stationary clamp and retaining fingers, and its lower end is beveled and rests upon the upper surface of a beveled operating block or wedge 13 mounted for sliding movement in guides 14 on the front portion of the base 2. The said lower end of the movable clamp carries at each side a guide pin 15 arranged for vertical movement in a slot 16 in the adjacent standard, by which the clamp is pivotally mounted for an inward and outward swing as well as an upward and downward sliding movement, the upper end of the clamp being supported and limited in outward movement by links 17 having hooked ends 18 to engage pins or projections 19 thereon.

After the oyster is placed upon the supporting shelf 11, the movable clamp is adjusted to a greater or less degree, according to the size of the oyster, to clamp the oyster between the same and the stationary clamp 6, with the butt end of the oyster disposed below the apertured projecting edge of the top wall 4. The means for effecting this adjustment comprises a compoundly curved link 20, having its upper end outwardly curved and pivotally connected with the movable clamp, as at 21, and its lower rearwardly curved end similarly connected with a pin or bolt 22 movable in an inclined slot 23 in the wedge block 13. Between its reversely curved ends or arms the lever is formed with a longitudinal slot 24 engaging a pivot pin 25 on the adjacent standard, by which said link is permitted to swing forwardly and rearwardly and to be adjusted

vertically with the movable clamp. To the pin 22 is also connected one end of an operating lever 26 pivotally mounted below the link and having its opposite end extending 5 beyond the frame to form a foot piece by which it may be depressed. Also connected with the pin 22 or with the block 13 is a coiled spring 27 which is attached to the adjacent rear standard and operates to re- 10 turn the parts to normal position.

When the lever 26 is operated, it will simultaneously serve to slide the wedge 13 outward and to swing the lever 20 to move the movable clamp inwardly. The inward 15 movement of said clamp brings the butt end of the oyster into engagement with the fixed clamp 6, while the wedge in such action will at the same time elevate the movable clamp, by which the butt end of the oyster will be 20 forced up into engagement with the projecting edge of the top wall, thereby firmly clamping the oyster in position to be operated upon by the knives.

A bar 28 is mounted to slide vertically 25 between the braces 5 and through guide openings in the top wall 4 and a lower guide member 29, and is provided at its upper end with a forwardly projecting arm or head 30 to which is hinged or pivoted a splitting 30 knife 31. As shown, the knife and head are formed with knuckles through which passes a pivot bolt 32 provided at one end with a clamp nut 33, whereby the bolt is retained in position. The knife has a lower pointed 35 end and normally inclines forwardly and downwardly and is adapted to be moved downward so that its pointed end will strike and sever the joint hinge of the oyster shell and partially separate the halves of the 40 shell at the butt. A lever 34 is pivotally mounted intermediate its length upon a pivot pin or bolt 35 carried by the head 30 and is held in position thereon by a thumb nut 36. The upper end of the lever is 45 formed to provide a handle, while its lower end has a downturned slotted portion 37, whose slot receives a guide pin or bolt 38 on the knife, which pin or bolt is threaded to receive a clamping nut 38' and extends outwardly at one side of the knife to provide a 50 contact arm 39.

By means of the lever the knife may be 55 adjusted to properly position it to operate upon large or small oysters, the slotted connection between the bolt 38 and part 37 adapting the knife and lever to respectively move in proper arcs for relative adjustment. After the knife is adjusted, the thumb nut 36 is tightened to a sufficient degree to hold the 60 knife firmly enough against movement to prevent deflection thereof when striking the joint of the oyster, but not to such an extent as to prevent a forward swing movement of the knife under a definite degree of pressure 65 thereon. The knife is adapted to be operated

through the medium of a lever 40 intermediately pivoted upon a pin or bolt 41 carried by the bar 28 and movable in a vertical slot 42 in the adjacent cross brace or plate 5, the lever also being provided with a slot in which the bolt is free to move to allow the lever to swing in its proper arc, whereby when the forward end of the lever is depressed the knife will be forced downwardly to penetrate and sever the hinge joint of the oyster against 75 the resistance of a weight or its equivalent 44 upon the rear end of the lever, by which the parts are returned to normal position.

It will be understood from the foregoing description that by the mechanism thus far 80 described the oyster may be clamped in position and the hinge joint connecting its shell sections severed and the halves of the shell partially separated at the butt. In addition, devices are provided for prying off the upper 85 shell and severing the same from the body of the oyster, leaving the latter within the lower half of the shell retained upon the shelf of the movable clamp. These devices consist of a prying and severing knife 45 fixed to and 90 projecting laterally from a plate 46 slidably mounted upon the top plate of the frame and having an inclined or cam surface 47 adapted to engage the contact 39. The slide 46 is retracted and held in normal position by a 95 spring 48 and is pivotally connected with an operating lever 49, as at 50; the lower end of said lever being pivotally connected with the adjacent underlying cross brace 5. The knife 45 has a forward beveled cutting edge and a 100 comparatively long rearwardly extending shank 51 which slides in guides 52 on the top plate. The slide 46 and the knife are fixedly connected for movement in unison, and after the knife 31 has been employed to open the 105 shell of the oyster at the joint and partly separate the shell sections, the lever 49 is moved forwardly transmitting corresponding motion to the knife and slide. The inclined edge 47 of the slide will bear upon and 110 engage the contact 39 and forcibly swing the knife 31 out of the path of the edge of the knife 45, which will engage the projecting edge of the upper half of the partially severed shell, sever the same from the body of the 115 oyster, leaving the latter upon the lower shell half, and discharge the upper shell half from the machine. Upon the release of the lever 49 the parts will be restored to normal position ready for the succeeding operation.

From the foregoing description, the construction and mode of operation of the apparatus will be readily understood, and it will be seen that it provides a device by which oysters varying in size may be conveniently 125 and expeditiously shucked.

Having thus fully described the invention, what is claimed as new is:—

1. An oyster shucking apparatus comprising a frame, oyster clamping means carried 130

thereby, means for severing the shell sections at the joint, and means for stripping away one of said shell sections.

2. An oyster shucking apparatus comprising a frame, oyster clamping means carried thereby, an adjustable knife for severing the shell sections of the oyster at the joint, operating means for said knife, a device operative to engage and strip away one of the shell sections, and means for operating the same.

3. An oyster shucking apparatus comprising a frame, oyster clamping means carried thereby, a splitting knife for severing the shell sections of the oyster at the hinge joint, means for operating said knife, a severing knife for engaging and stripping away one of the shell sections, and means for operating said stripping knife.

4. An oyster shucking apparatus comprising a frame, oyster clamping means carried thereby adapted to hold the oyster for the exposure of the hinge joint thereof, a knife operative to sever said joint and separate the shell sections at the butt, a second knife operative to enter between the separated portions of the shell and strip one shell section away from the oyster, and means for operating the respective knives.

5. An oyster shucking apparatus comprising a frame, means for holding an oyster to be shucked, means for splitting the hinge joint of the shell, and means for removing one of the shell sections.

6. An oyster shucking apparatus comprising a frame, means for holding an oyster to be shucked, a knife operative for splitting the hinge joint of the shell, a second knife movable past the first-named knife and adapted to engage and strip away one of the shell sections, and operating means for successively actuating said knives.

7. An oyster shucking apparatus comprising a frame, clamping means for holding an oyster in an inclined position with the jointed end of the shell uppermost, a knife for splitting the hinge joint, guiding and operating means for said knife, a second knife adapted to engage and remove one of the shell sections, and operating means for said knife including means for moving the first-named knife out of path of movement of the second-named knife.

8. An oyster shucking apparatus comprising a frame, fixed and movable clamps carried by the frame, means for operating the movable clamp, a knife movably mounted upon the frame and operative to split the hinge joint of the clamped oyster, means for adjusting and operating said knife, a second

knife movable past the splitting knife to engage and strip away one of the shell sections, means for operating said stripping knife, and means coacting with said stripping knife for moving the splitting knife out of the path of motion thereof.

9. An oyster shucking apparatus comprising a frame, means for clamping an oyster in an inclined position with the jointed end of the shell uppermost, a pivotally supported adjustable splitting knife movable in a path to split the hinge joint, means for adjusting and operating said knife, a sliding knife movable across the path of the splitting knife and adapted to engage and strip away the upper shell section, and means for operating said sliding knife, said means including a device for moving the splitting knife out of the path of the severing knife.

10. An oyster shucking apparatus comprising a frame carrying a stationary clamp, a cooperating clamp mounted for swinging movement towards and from said stationary clamp and sliding movement in a vertical plane, means for actuating said movable clamp, a splitting knife for severing the hinge joint of the oyster held by the clamp, means for operating said knife, and a severing knife for stripping away one of the shell sections of the oyster, and operating means for said severing knife including means for adjusting the splitting knife out of the path thereof.

11. In an oyster shucking machine, means for clamping an oyster, an adjustable knife for splitting the hinge joint of the oyster shell, a severing knife for stripping away one of the sections of the oyster shell, said knives being movable in intersecting paths, and operating means for said knives including means for moving one out of the path of the other.

12. In an oyster shucking machine, a frame carrying a stationary clamping member, a pivotally mounted coacting clamping member, said clamping members being adapted to hold an oyster in an inclined position with the hinge joint of the same adjacent the stationary clamp, a splitting knife movable in an inclined path to sever the joint, a severing knife movable in a different path to strip away the upper shell section of the oyster, and means for operating the knives.

In testimony whereof I affix my signature in presence of two witnesses.

WILLIAM KLINGE.
